UNITED STATES PATENT OFFICE.

BENJAMIN F. SCHMIDT, OF MODESTO, CALIFORNIA.

NAIL-HOLDING ATTACHMENT FOR DRIVING-TOOLS.

No. 845,823.

Specification of Letters Patent.

Patented March 5, 1907.

Application filed February 27, 1906. Serial No. 303,261.

To all whom it may concern:

Be it known that I, BENJAMIN F. SCHMIDT, a citizen of the United States, residing at Modesto, in the county of Stanislaus and State of California, have invented a new and useful Nail-Holding Attachment for Driving-Tools; and I do hereby declare the following to be a full, clear, and exact description of the invention, such as will enable others skilled in the art to which it appertains to make and use the same.

The invention relates to nail-holding attachments for hammers or any driving-tool for nails, tacks, and the like, and has for its object to provide a device of this character which will hold nails by their heads while being started into the wood into which they are to be driven.

In the drawings forming part of this specification, and in which like numerals of reference designate corresponding parts, Figure 1 is a perspective view of my invention shown applied to a hammer. Fig. 2 is a sectional view on line 2 2 of Fig. 1. Fig. 3 is a detail view of the attachment disengaged from the hammer. Fig. 4 is a perspective view of my invention, showing two sizes of nail-holding slots. Fig. 5 is a longitudinal sectional view taken on line 5 5 of Fig. 4. Fig. 6 is a view of my invention, showing a modified form. Fig. 7 is a detail perspective view of the nail-holder shown in Fig. 6.

Referring to the drawings, 1 designates the base of the hammer attachment, being of tapering thickness, as shown at 2, and provided upon one side is a plurality of pointed lugs 3, which are adapted to be forced into the handle of the hammer for the purpose of coöperating with the eye of the hammer in preventing displacement of the attachment. The base portion 1 is connected with the body portion 5 by a connecting portion 4, as shown in Figs. 1 and 2. The body portion 5 is provided with a V-shaped slot 6, which engages the head of the nail or tack to be driven, as will be readily understood.

Figs. 5 and 6 show the body portion 5 pivotally connected with the base portion 1 by a pivot 4^a, by which the said body portion 5 may be rotated, thus affording means for engaging the heads of large or small nails, the said body portion being provided with a slot at each end, which are of different shapes and sizes and may be varied according to the use to which the device may be put, and one slot 55 may be adapted to hold nails and the other may be much smaller for the use of tacks and the like. The slotted plate or body portion 5, as shown in Fig. 5, is provided with lugs 5^a, which engage recesses for the purpose of holding the portion 5 against rotation. The portion or plate 5 is of course resilient and can be readily sprung, so as to disengage the lugs 5^a from the recesses when it is desired to rotate the same.

In Figs. 6 and 7 the body portion or plate 5 is somewhat elongated, which admits of being bent upon itself, whereby it by being placed on the proper part of the hammer can coöperate with the claws of the same in holding the nail more securely for starting the same. The eye of the hammer is recessed, as at 9, for the reception of the base portion of the device.

What I claim is—

A hammer having a plate rigidly secured to the same, a second plate pivotally mounted on said first-named plate, and adapted to revolve thereon and having V-shaped openings at each end thereof for holding nails of varying sizes, and lugs mounted on said revolving plate, adapted to engage recesses in said rigid plate, substantially as described.

In testimony whereof I have hereto affixed my signature in the presence of two witnesses.

BENJAMIN F. SCHMIDT.
